UNITED STATES PATENT OFFICE.

JOHN GLENNIE HOLBOURNS AND HENRY ALEXANDER LONGHURST, OF LONDON, ENGLAND.

ESCAPEMENT MECHANISM OF LINOTYPE-MACHINES.

No. 832,792.

Specification of Letters Patent.

Patented Oct. 9, 1906.

Application filed April 16, 1906. Serial No. 311 971.

To all whom it may concern:

Be it known that we, JOHN GLENNIE HOLBOURNS and HENRY ALEXANDER LONGHURST, of 188 Fleet street, London, England, have invented new and useful Improvements in the Escapement Mechanism of Linotype-Machines; and we do hereby declare the following to be a full, clear, and exact description of the invention, such as will enable others skilled in the art to which it appertains to make and use the same.

The present invention relates to improvements in the escapement mechanism of linotype-machines, more especially in that of the commercial Mergenthaler linotype-machine described in the specification of Letters Patent No. 436,532. The matrices of this machine are arranged according to character in columns or channels in a magazine, all the 15 matrices of the same character in one channel. The matrices in each channel are retained within the magazine by an escapement, the set of escapements being under the control of a keyboard. They pass from the 20 magazine one by one and in the order in which the keys of the keyboard are manipulated, together with the necessary space-bars from the space-bar magazine, to the assembly-box, from which a composed line of them 25 is transferred to the shifter, which in its turn transfers the line to the first elevator. This elevator presents the line to the casting mechanism which casts the corresponding linotype. After the linotype has been cast the 30 same elevator delivers the composed line of matrices to the distributor, which proceeds to return the matrices to the magazine, each matrix being returned to its proper channel, but to the opposite end of it. Thus each matrix 35 in turn and on the initiative of the respective key passes through the same cycle of motion. Sorts-matrices are kept in a sorts-box and put into the assembly-box by hand and are rejected by the machine between the first elevator and the distributor, 40 when they drop into the pi-box. They are taken out of the pi-box and returned to the respective compartments of the sorts-box by hand. Thus a sorts-matrix shares with magazine-matrices only a small portion of their 45 cycle of motion.

A magazine-matrix stands in and moves through the magazine with the side edge that has the character-cavity downward, the two

pawls of the escapement that controls that 55 standing and passage coöperating with a lug projecting downward from the said side edges of each two leading matrices, these pawls working vertically in the plane of the matrices. The character-cavity being wholly recessed within the body of the matrix never gets in the way of the pawls.

The specification of Letters Patent to Whitaker, No. 691,685, dated January 21, 1902, and to Speechley, No. 793,691, dated July 4, 1905, describe matrices for forming seatings or recesses in linotypes to receive column-rules. These matrices are characterized by flat projections or tongues projecting from them in proper position for entering and 60 cornering the mold. They take the place on the side edges of the matrices of the character-cavities of the magazine-matrices. It has been found that such a projection or tongue tends to get in the way of the rear one of the 65 two escapement-pawls and to jam the escapement. The specification of Letters Patent No. 691,685 speaks of its column-rule matrices being composed into the assembly-box by the keyboard-actuated escapement in 70 the same way as the ordinary matrices (and therefore from the magazine) and that of Letters Patent No. 793,691 speaks of them as being distributed to the magazine, but neither of them describe how that composition 75 is to be effected. It has consequently been the practice up to the present time to treat these column-rule matrices as sorts-matrices; but as it takes longer to compose sorts-matrices by hand than it does to compose magazine-matrices from the keyboard and as such hand composition costs more than keyboard composition it is obvious that a double advantage would be derived from the presence 80 of the above-described column-rule matrices 85 in the magazine under the control of the keyboard and of their being made in all other respects capable of sharing the full cycle of the magazine-matrices.

The principal objects of the present invention are to make these column-rule matrices capable of sharing the above-named full cycle, and, further, to enable the escapement appertaining to the channel containing such rule-matrices to be coupled to one or more of 90 the other ordinary escapements, so that the operation of the first-named escapement will be immediately followed by the automatic 95 100 105

operation of the other escapement or escapements coupled thereto in proper sequence, so as with one depression of a key-lever to bring down into the assembly-box all the 5 matrices required to produce any oft-repeated combination, word, or syllable.

The invention will be best understood by reference to the accompanying drawings, and the essential features of novelty are hereinafter fully described, and more particularly 10 pointed out in the claims.

In the drawings, Figure 1 is an elevation, viewed from the left-hand side of the machine and shown partly in section, of as much 15 of the apparatus as is necessary to illustrate this invention. Fig. 2 is a plan of Fig. 1 with parts omitted. Fig. 3 is a plan corresponding to a part of Fig. 2, but showing the devices in a different position. Fig. 4 is a 20 detail view of the escapement. Fig. 5 is a perspective view showing the manner in which the apparatus is applied to the machine, only a portion of which is represented and that in dotted lines. Fig. 6 is a perspective view, and Figs. 7, 8, and 9 are vertical 25 sections of the coupler devices.

In carrying out this invention we preferably utilize the leftmost of the channels of the magazine 1 for storing the column-rule 30 matrices 2, for the reason that this channel is generally a spare one, there being usually ninety-one of such channels in the ordinary commercial linotype-machine, of which only ninety are usually employed and provided 35 with escapements.

By referring to Fig. 1 it will be seen that each of the column-rule matrices 2, which are in that figure represented in dotted lines, is provided with the well-known distributing- 40 teeth 2^a, whereby it is adapted for automatic distribution by the usual distributor mechanism and also with one of the before-mentioned flat projections or tongues 3, which latter when the said matrices are stored in 45 the magazine 1 are presented downward. It is for that reason that the existing form of escapement is not found suitable, because as the two escapement-pawls thereof work through the bottom of the magazine the rear one of 50 such pawls would foul or be fouled by the projections 3, and thereby cause a jamming of the escapement. To avoid such a defective working, the escapement-pawls 4, 5 are arranged to work through the side 6, Figs. 2 and 55 3, of the magazine, the said pawls, as shown in Figs. 1, 2, 3, and 5, entering the magazine horizontally and working in an inclined plane above the path of the projections 3.

The outer ends of the pawls 4, 5 are suitably pivoted to an inclined lever 7, adapted to oscillate upon a pivot or screw 8, fast to a block 9, rigidly attached to the side of the magazine. The lever 7 is in engagement 60 with the upper end of a lever 10, adapted to 65 be rocked in a vertical plane upon a pivot or

screw 11, projecting horizontally from the left side of the block 9. The lever 10 is acted upon by a spring 12, which constantly tends to move its lower part forward—that is to say, toward the right of Fig. 1—and thereby 70 withdraw the escapement-pawl 4 from the path of the column-rule matrices 2, as shown in dotted lines in Fig. 3. At its lower end the lever 10 is provided with a forwardly-projecting tail 13, or an antifriction-roller, 75 adapted to be held by the spring 12 in constant contact with the rear edge of a vertical escapement-rod 14, which is guided at its upper end by a clip or guide 15, fast to the block 9, and at its lower end in a guide 16, 80 provided at the rear end of a bracket 17, which is rigidly attached to any convenient part of the machine-frame, a portion of which is represented by the dotted lines 18 in Fig. 5. The rear edge of the escapement-rod 14 is 85 formed with a recess 19, adapted to receive the tail 13 when this rod is raised sufficiently to present the said recess to the tail. When the rod is in its lower position, the tail 13 bears on the cam projection 20, as indicated 90 in Fig. 1. The escapement-rod 14 is acted upon by a tension-spring 21, which constantly tends to draw it downward or to return it after it has been raised to its lowermost position, and it is engaged with the rear end of a 95 key-lever 22, pivoted to the bracket 17 and conveniently located near the left hand of the existing keyboard. The lowermost position of the escapement-rod 14 is determined by a stop-pin 23, projecting below the rear end 100 of the key-lever 22, as shown in Figs. 1 and 2.

Upon the escapement-rod 14 there is adjustably secured—as, for example, by a pinching-screw 24—a collar 25, adapted to engage with the under side of the rear end of a pin 26, passing diametrically through a rocking shaft 27, which extends in front of this escapement-rod, as well as in front of all the other usual escapement-rods, and at its ends the said rocking shaft is supported in 105 suitable bearings 28, only one of which is shown in Fig. 5. The pin 26 is free to turn in and to slide in the direction of its length through the rocking shaft 27 and is provided with a head 29 and a cross-pin 30, the latter 110 of which is adapted to fit into a groove 31. (Shown in dotted lines in Figs. 1, 7, and 8.) Between the rocking shaft 27 and the head 29 there is provided a compression-spring 32, which constantly tends to move the pin 26 in 115 a forward direction farther away from the escapement-rod 14, so as to be out of reach of the adjustable collar 25, as represented in Fig. 8. When the pin is required in operation, the cross-pin 30 is turned across the 120 mouth of the groove 31, as indicated in Figs. 1 and 7, so that the said pin 26 is retained in its rearmost position, in which it extends into the path of the collar 25. The rocking shaft 27 is also provided with a rib 33, Figs. 125 130

6 and 9, which is of sufficient length to extend in front of all of the usual escapement-rods 34 or as many of them as may be required to be included in any coupled combination. In Fig. 6 only two of the rods 34 are represented and these on an exaggerated scale and at an exaggerated distance apart. This rib 33 projects close up to the front edges of the escapement-rods 34 and is adapted to engage with the under sides of collars 35 36, adjustably secured—as, for example, by pinching-screws 37—on the respective escapement-rods 34. The collars 35 36 are secured in different positions on their respective rods 34, so that the rib 33 shall contact therewith in the order in which the respective matrices are to be released to form the desired sequences or combinations in the assembly-box.

20 The respective positions of the before-described top of the escapement-rod 14, the cam projection 20, recess 19, tail 13 on the lever 10, and spring 12 may be changed, provided that the following functional relationships be preserved.

25 When the key-lever 22 is at rest, as indicated in Figs. 1 and 2, the cam projection 20 is in engagement with the tail 13, thereby holding the front pawl 4 rocked into the magazine in front of the leading or lowermost of the column-rule matrices 2 and the rear pawl 5 clear of the said matrices against the pressure of the spring 12, as best illustrated in Fig. 2. The escapement-rod 14 is held with its cam projection 20 in the position just mentioned, partly by its own spring 21 and partly by its weight, the stop 23 preventing it from being pulled or dropping below this point.

30 When the key-lever 22 is depressed—and it is depressed to release a column-rule matrix 2—the escapement-rod 14 is raised in its guides 15 and 16 against the pull of the spring 21, thereby carrying the cam projection 20 away from the tail 13 and presenting the recess 19 to the latter, into which it is forthwith pushed by the spring 12. This makes the escapement-lever 7 move the front pawl 4 from before the leading matrix 2 (which 35 forthwith drops from the magazine 1) and the rear pawl 5 in front of the second matrix, as indicated in Fig. 3. When the key-lever 22 is released, the spring 21 pulls the cam projection 20 downward into its original position, thereby reversing the escapement-pawls 4 and 5 in time to admit of the pawl 4 stopping the then leading matrix, as indicated in Fig. 2.

35 By attaching the block 9 to the side of the magazine 1 and by the manner in which the lever 10 is operated by the escapement-rod 14, as hereinbefore described, the changing of the magazines, as hitherto practiced for obtaining a change of font, is in no way interfered with.

In composing tabular matter the operator has generally to compose a considerable number of oft-recurring and identical sequences or combinations, which, unless special provision be made, necessitates the depression of all the individual key-levers to release the several matrices corresponding to those combinations. As an example of such a combination attention may be directed to railway time-tables, wherein many repetitions, such as the following, are to be found, viz: rule, en-quad, leader, and em-quad. To compose such a combination on the ordinary linotype-machine necessitates four separate depressions of the respective key-levers; but by the present invention the same result may be obtained by a single operation. For this purpose it is necessary to adjust the respective collars 35 36, &c., so that the parts immediately concerned in the operation shall be caused to operate in the following order: The key-lever 22 is depressed to release the necessary column-rule matrix 2, (and this is the only operation necessary on the part of the operator,) and this operation, besides releasing the said matrix 2, through the pin 26 rocks the shaft 27, which, through its rib 33 and the respective collars 35 36, &c., first raises the escapement-rod appertaining to the en-quad, then that appertaining to the leader-matrix, and then that appertaining to the em-quad, these movements of the said escapement-rods following each other at the intervals apart necessary for allowing the matrices and quads to reach the assembly-box in the desired order of composition.

If the sequence or combination which is frequently recurring consists of the three last of the four matrices given in the preceding example, then the key-lever 22 may still serve for composing it at one operation. This result may be obtained by either emptying the magazine-channel containing the column-rule matrices 2, in which case the operation of the escapement-pawls 4 5 would have no effect, or the said channel may be retained full of matrices and the ascent and descent of the escapement-rod 14 be rendered ineffective upon the escapement-pawls 4 5, which latter result may, for example, be secured by inserting a pin or equivalent (not shown in the drawings) in a hole 38, Fig. 1, provided for the purpose, close to the back of the upper end of the lever 10, and which pin would serve to prevent the said lever from rocking on its pivot 11.

There are numerous other frequently-recurring sequences or combinations of matrices or slugs for the composition of which the before-described devices may be employed, with great advantage and economy. For example, in newspapers there are frequently to be found whole columns of advertisements commencing with the word "Wanted," the initial letter of which (as

provided for by Letters Patent No. 551,981) for display purposes occupies the space of or extends over two lines. The matrices for producing these two-line letters have hitherto been treated as sorts-matrices and have consequently been composed into the line by hand, involving in the case of frequent repetitions, such as just mentioned, a considerable expenditure of time. According to the present invention these two-line matrices would be dealt with as ordinary matrices and would be provided with distributer-teeth, such as 2^a in Fig. 1, and contained in the leftmost magazine-channel. With these two-line matrices so stored in the magazine 1 a single depression of the key-lever 22 may be caused to release all the matrices appertaining to the word "Wanted" by adjusting the collars 35 36, &c., appertaining to the respective "a," "n," "t," "e," and "d" matrices so that these latter shall be released in the desired order of composition. Numerous other examples of these frequently-recurring displayed advertisements might be mentioned, and all capable of being dealt with in a manner corresponding to that previously described, but their enumeration would serve no useful purpose.

In lists of names the abbreviation "Esq." frequently recurs, and the matrices may therefore all be released by a single depression of the key-lever 22 after having first made the necessary adjustments for rendering the operation of the escapement-rod 14 ineffective upon the escapement-pawls 4 5 and effective upon the escapements appertaining to the "E," "s," "q," and " ." matrices.

In subscription-lists there generally are numerous repetitions of the sequence comprising a leader, an em-space, and a leader, and by means of this invention the matrices and quads appertaining to such a sequence may be released all by one depression of the key-lever 22.

In the composing of addresses in linotype-machines there is a considerable amount of quadding necessary, and this work may be greatly facilitated by the present invention, because the leftmost of the magazine-channels may be charged with em-quads and the coupler be arranged to couple the escapement of this channel with those of the ordinary em and en quad channels, so that by each depression of the key-lever 22 two em-quads and one en-quad will be added to the assembling-line. This capacity is of course additional to that which provides for the assembling of the em-quads and en-quads independently of each other, this being effected by depressing their respective key-levers as ordinarily.

A further advantageous use to which this invention may be put is to provide for the release by one depression of the key-lever 22

of two similar letters for assembling matrices for forming words such, for example, as "street," "need," "feed," "meet," &c., and this result may be attained by charging the leftmost of the magazine-channels with "e" 70 matrices and so adjusting the before-described coupling devices that the depression of the key-lever 22, besides operating the escapement-pawls 4 5, also operates the escapement of the ordinary "e" matrix channel. 75 Similar provision may of course be made for double letters other than "e's," the "e" example being given only by reason of its being found to recur more frequently than any others. 80

When it is required to release only the matrix stored in the leftmost magazine-channel as distinguished from that matrix plus the others for which the coupler devices had last been adjusted, the operator withdraws 85 the before-described pin 26 into the inoperative position, in which it is represented in Fig. 8, and then depresses the key-lever 22, this depression then having no effect upon the rocking shaft 27. 90

It is to be observed that the foregoing devices, while enabling the depression of a single key-lever to effect the release of a sequence of matrices, in no way prevents each of such matrices being, as ordinarily, released 95 by its own individual key-lever, and it is to be further observed that, as the escapement mechanism hereinbefore described is specially designed for controlling the release of column-rule matrices stored in the leftmost 100 magazine-channel, when that channel is not intended to be used for those matrices the said channel may be provided with an escapement of ordinary construction, the rod of this escapement being adapted to rock the 105 shaft 27 in the same manner as that already described and shown in Figs. 1 and 7.

It has hitherto been proposed to provide linotype-machines with special key-levers which at each depression would release certain definite sequences of matrices; but these devices have admitted of no variation or adjustment, so that if a frequently-recurring sequence occurs in the job in hand, which sequence is not provided for by these 115 special key-levers, such matter must be composed by operating the individual key-levers. It has also been proposed to provide these machines with a rotating barrel which by means of projecting pins would actuate certain prearranged series of key-levers, these in turn operating the respective escapements for releasing the desired sequence of matrices; but this arrangement does not lend itself to ready adjustment and is, moreover, costly in 120 its construction and application. The before-described apparatus, unlike those last mentioned, combines the facility for adjustment with economy in construction and application. 125 130

We claim—

1. In a linotype-machine the combination with the leftmost channel of the magazine, of an escapement, an escapement-rod and key-lever therefor, a rocking shaft adjacent to the said escapement-rod, the ordinary escapement-rods, and devices adapted to operatively connect this shaft with all of the escapement-rods.
- 10 2. In a linotype-machine the combination with the leftmost channel of the magazine, of an escapement, escapement-rod and key-lever therefor, a rocking shaft adjacent to the said escapement-rod, the ordinary escapement-rods, and a device adapted to place the said shaft in and out of operative connection with this escapement-rod.
- 20 3. In a linotype-machine the combination with a magazine-channel of two escapement-pawls adapted to horizontally reciprocate through one side, as distinguished from the back or front, of the said channel, and a key-lever operatively connected with the said pawls adapted to reciprocate them.
- 25 4. In a linotype-machine the combination with one of the outermost channels of the magazine, of two escapement-pawls adapted to horizontally reciprocate through one side, as distinguished from the back or front, of the said channel, and a key-lever operatively connected with the said pawls adapted to reciprocate them.
- 35 5. In a linotype-machine the combination with one of the outermost channels of the magazine, of two horizontal escapement-pawls adapted to horizontally reciprocate through one side of the said channel, a lever in pivotal connection with both of these pawls and pivoted to turn on an axis perpendicular to the inclined plane of the magazine and an escapement-rod in operative connection with the said lever.
- 40 6. In a linotype-machine, the combination with one of the outermost channels of the magazine, of two horizontal escapement-pawls adapted to horizontally reciprocate through one side of the said channel, a lever in pivotal connection with both of these pawls and pivoted to turn on an axis perpendicular to the inclined plane of the magazine, a vertical lever engaging the first-named lever adapted to rock in a vertical plane, and an escapement-rod and spring engaging the ver-

tical lever and adapted to rock it in a vertical plane.

55

7. In a linotype-machine the combination with the escapement-rods, of a rocking shaft adjacent thereto, devices operatively connecting one of the escapement-rods with the rocking shaft adapted to rock the latter, and devices operatively connecting the other escapement-rods with the rocking shaft adapted to impart longitudinal motion to the said rods.

8. In a linotype-machine the combination with the escapement-rods, of a rocking shaft adjacent thereto, a collar on one of the rods, a projection on the rocking shaft adapted to project into the path of the collar and means adapted to retain the said projection in and out of the path of the collar.

9. In a linotype-machine the combination with the escapement-rods, of a rocking shaft adjacent thereto, collars on the said rods, a projection on the rocking shaft adapted to contact with the collars, and devices on the collars for enabling them to be adjusted in and out of reach of the projection.

10. In a linotype-machine the combination with the escapement-rods, of a rocking shaft adjacent thereto, devices operatively connecting one of the escapement-rods with the rocking shaft adapted to rock the latter, said devices capable of being rendered inoperative, and devices operatively connecting the other escapement-rods with the rocking shaft adapted to impart longitudinal motion to the said rods.

11. In a linotype-machine the combination with the escapement-rods, of a rocking shaft adjacent thereto, devices operatively connecting one of the escapement-rods with the rocking shaft adapted to rock the latter, and devices operatively connecting the other escapement-rods with the rocking shaft adapted to impart longitudinal motion to the said rods both sets of devices being capable of being rendered inoperative.

In witness whereof we have hereunto set our hands in the presence of two witnesses.
